FLUID PUMP

Joseph W. Murphey, Monroe, La.

Application August 18, 1933, Serial No. 685,782

6 Claims. (Cl. 103—260)

My invention relates to fluid pumps.

An object of my invention is to provide a fluid pump for use in oil wells and gas wells that will operate satisfactorily on a low pressure fluid supply.

Another object of my invention is to furnish a well blower that is cheaply and simply constructed and simple in its operation.

Other objects and advantages of my invention will appear in the description of my invention to follow.

In the accompanying drawing forming a part of this application and in which like numerals are employed to designate like parts throughout the same,

Fig. 1 is an elevational view in part cross section of my invention.

Fig. 2 is an enlarged fragmentary elevational view in part cross section of a part of my invention.

Fig. 3 is a cross sectional view taken on line 1—1, of Fig. 2.

Fig. 4 is a cross sectional view taken on line 2—2, of Fig. 2.

Fig. 5 is a fragmentary elevational view in partial cross section of another modification of my invention.

Broadly speaking my invention is comprised of a tubular shell adapted to be lowered down into a liquid by means of a line of pipe, to the end of which it is attached. A suitable fluid conduit is extended inside or along the line of pipe. The fluid conduit terminates at a point within the shell at a point about midway its length in upwardly directed nozzles.

Below the nozzles there is a partition in the shell which carries check valves through which the liquid to be pumped may enter. Above the nozzles there is located another partition carrying another set of check valves. These upper check valves are positioned immediately above the aforementioned upturned nozzles and in direct alignment with them.

In the operation of this pump, streams of fluid under pressure issuing from the nozzles strike the movable valve closing elements directly and cause them to lift from their seats and allow liquid to pass. The fluid which passes through and opens the valves we will call the operating fluid. The operating fluid in passing through the valves carries with it some of the liquid L to be pumped.

In the operation of this type of fluid pump with air, gas, or steam as the operating fluid, it has been found that the action of the operating

fluid on the liquid supply created a column of foam above the upper check valves. As this column of foam above the operating fluid nozzles is very light, it offers but little resistance in the operation of the pump. As fast as the supply of liquid entrapped in the casing is pumped up, more liquid comes in through the lower check valves to take its place.

This pump pumps liquid continuously as long as the operating fluid supply is maintained.

The check valves during the operation of the pump are held open normally. However, the valves will shut off the pump when the operating fluid supply is shut off.

Under suitable conditions this pump will operate without any valves at all.

In lifting the valve closing elements, the operating fluid is spread to good effect in that it is more thoroughly mixed with the liquid that it is lifting. That is to say the valve closing element spreads the operating fluid out into a cone-shaped film before it can pass through the peripheral opening through the valve as defined by the ball and the seat it normally rests on. The fluid being pumped also has to pass through this same peripheral opening and in so doing it becomes intimately mixed with the operating fluid itself. When the operating fluid used is a gas the intimate mixture of the operating fluid and the liquid pumped results in a very light foam that is easily blown upwardly. Thus we see that these upper check valves serve a double function, the regular function of a check valve and the additional function of a mixing valve.

This type of fluid pump is well adapted to pump oil or water from oil wells or gas wells, and it is in these particular uses that its further description will be directed. But it is to be understood that the invention is in no wise limited to use in oil wells and gas wells for it has a broad application in various forms and sizes in the practice of pumping fluids.

In the preferred form of my invention shown in Figs. 1, 2, 3, and 4 numeral 1 denotes generally the fluid pump. Numeral 2 denotes a shell. The shell 2 has a threaded portion 3 at its upper end, adapting it to be joined to a string of pipe 50 of sufficient length to place the pump shell 2 a short distance below the surface of the liquid L to be pumped from a well casing 100. The shell is preferably made in the shape of a cylinder circular in cross section.

The shell consists of an expanded cylindrical portion 4 converging at each end into straight sections of less diameter. The upper end of this

shell is the aforementioned portion 3 to which the string of pipe 50 is attached. The lower portion of the shell designated by numeral 5 is closed by a cap 6.

5 The lower portion of the shell 2 is provided with perforations 7 of a size suitable to admit the liquid to be pumped, but small enough to strain out foreign matter which might interfere with the operation of the pump.

10 Located immediately above the perforated section there is mounted in the shell 2 a valve cage partition 10. This valve cage partition is externally threaded throughout its length and serves to join two internally threaded sections of the shell 2 in end abutting relationship.

15 At a point in the shell above the partition 10 at a distance of about four times the diameter of the expanded portion of the shell there is located a similar externally threaded valve cage partition 20, which also serves to join sections of the shell in end abutting relationship. A fluid chamber is formed by the shell and the two valve cage partitions.

20 The valve cage partition 10 is suitably cored through to permit the passage of liquid and to carry two check balls 11 which normally rest on seats 13. The seats 13 may be formed as an integral portion of the cage proper or made in the form of replaceable seat rings.

25 The check balls are checked in their upward travel by closure members 14 which include cross bars 15.

30 In oil and gas well practice the shell of my pump would be made about four inches in diameter in its expanded portion.

35 The valve cage partition 20 is flared at its lower end at 21 for the purpose of providing a smooth entrance to the valve openings for the liquid L and operating fluid to flow through. This second valve cage partition 20 is provided with two check balls 22 which normally rest on two suitable valve seats 23.

40 While my invention is illustrated with two nozzles and two sets of twin check valves, it is to be understood that this type of pump may be constructed with one, two, or more nozzles and corresponding suitable valves. The bottom valve means in any case may be a single valve if desired.

45 These check balls 22 are checked in their upward travel by cross bars 15 mounted at the upper ends of cylinders 24 extending upwardly from the valve cage partition 20. These cylinders are expressly made perforated to finely divide 50 the combined stream of operating fluid and liquid L. By means of the addition of the openings 24 the effective opening area above the balls 22 is increased with the result that the back pressure at this point is reduced to a minimum.

55 60 We come now to the means by which the operating fluid used is supplied to my pump. The operating fluid in oil and gas well practice is generally compressed air, steam, or natural gas under its own natural pressure.

65 70 In Fig. 1 the operating fluid is conducted through a supply pipe 30 which is extended down from a power source not shown.

Attached to the lower end of the supply pipe 30 there is a lead-in tube 31 which is passed through and secured to the cage partition member 26 at a point about midway between the upper valve cage partition 20 and the lower valve cage partition 10.

75 The lead-in tube 31 is connected into a U shaped tubular member 32 so that its branches 33

extend upwardly. Threadedly attached to the end of the branches 33 there are collar members 34. The upper inner peripheries of the collars 34 are formed into valve seats to carry check balls 35. The collars 34 are threaded on their outer surfaces to carry shells 36.

5 Cross bar members 38 are clamped between the collar members 34 and nozzles 39.

The contracted tips 40 of the nozzles are shown in Fig. 2 as located within the coned shaped 10 spaces 21 of the valve cage partitions 20. In this position the streams of operating fluid are directed at the centers of the check balls 22.

15 In the operation of this pump it is the kinetic energy of the flowing fluid that is depended on 15 to lift the balls 22 rather than the static pressure of the operating fluid. In this respect its operation is radically different from other devices.

20 However in this device the static pressure of the fluid being pumped, combined with static 20 pressure of some of the misdirected operating fluid, does have some additional effect in the lifting of the check balls.

25 The check balls 22 serve to spread the stream of operating fluid as it passes through the valve 25 passage. The stream of operating fluid takes on the shape of a hollow cone similar to the spray from a common lawn hose nozzle.

30 All the time that the operating fluid is passing through the valve openings, the liquid L is being 30 urged up through these same openings by the pressure derived from its own head. It is also being sucked in around the nozzles 40 and being carried through these openings by the force of the operating fluid jets. The result of the mixing 35 of a gaseous operating fluid on oil or water is the formation of a column of foam above the upper valves. This column of foam is very light in weight and offers but little resistance to the flow of the operating fluid.

40 45 The column of foam in its travel upward of the shell is necessarily speeded up at the contracted portion 3 of the shell 2. This foam mixture comes out of the pump at the surface of the ground sometimes in the form of foam and sometimes in 45 the form of a spray or in small slugs of liquid.

50 55 In the modified form of my invention illustrated by Fig. 5, its shell 60 is the same as the shell of the preferred form of my invention. The casing 60 is provided with a valve cage partition 61 of the same general design as the lower valve cage of the preferred form of my invention. The upper valve cage partition 62 is of the same general design as the upper cage partition 20 of the preferred form of my invention.

55 60 In this form of my invention, the opening through the lower cage partitions are connected directly to the opening of the upper cage partition by means of conducting tubes 63. These conducting tubes for convenience in assembly are 60 made in two lengths and joined together by a distributing block 65 which is itself threaded to the casing 60.

65 70 The upper and lower sets of check valves function in the same way as the corresponding valves 65 of the preferred form of my invention. The operating fluid line 66 of this form of my device is extended to a central portion of the shell 60 through the shell 60 at a point 67 through a suitable reinforcing slug 68. It is extended thence 70 upwardly along side of the small neck portion of the casing on up to a source of fluid supply close to and along the string of pipe that supports the shell.

75 This modification provides for a very free pas- 75

sage for the generated foam. In this form of my invention the fluid line may be disassembled independently of the string of pipe which supports the shell.

5 The check valve in this form of my invention is located on the main fluid line and is designated by numeral 69.

10 The upwardly turned branches of the U shaped members in this form of my invention constitute the nozzles.

These upwardly turned branches 10 are ended close to the balls 71 in the valve cage partition number 62 and are aimed at them.

15 This second form of my invention above described operates on the same principle as does the preferred form of the invention.

These various parts of my invention may be made of steel, bronze or other suitable materials.

20 Having thus described my invention what I claim is:

1. A well pump comprising a flow pipe including an elongated shell, a fluid conducting means extending into the shell including an upwardly directed nozzle, a check valve means in the shell 25 below the nozzle constituting a closure in the shell, a second check valve means including a ball in the shell above the nozzle, said second mentioned check valve means constituting also a closure means in the said shell, the said ball 30 being located adjacent the opening of the nozzle whereby to flare a stream of fluid issuing from the nozzle.

2. A well pump comprising a flow pipe including an elongated shell, a fluid supply means 35 passed through a wall of the shell and terminating in upwardly directed nozzles, a valve cage partition means having passages therethrough provided with movable valves located in the shell below the nozzles, a second valve cage partition 40 having passages therethrough provided with movable valves located above the nozzles, and con-

ducting tubes surrounding the said nozzles connecting the passages through the lower valve cage partition to the passages through the upper valve cage partition.

3. The device as claimed in claim 2 having the fluid supply means passing through the end wall 5 of the shell and extending upwardly of the shell parallel to the longitudinal axis of the shell.

4. A well pump comprising a flow pipe, a fluid supply pipe terminating in a plurality of upwardly directed nozzles at one end of the said flow pipe and a partition member in the flow pipe located immediately above the nozzles and provided with a number of check valves equal to the number of nozzles and in alignment with the 10 same and a second partition member provided with check valve means located in the said flow pipe below the said nozzles.

5. In a well pump the combination of a flow pipe, a fluid conduit terminating in an upwardly 20 directed nozzle within the flow pipe and a partition member in the flow pipe immediately above the nozzle provided with check valve means including a valve seat and a slidable closing element adapted to flare a jet of fluid, said partition 25 member being provided with an opening leading to the said valve seat, the smallest diameter of the said opening being approximately the same as the smallest diameter of the actual seating surface of the said valve seat, whereby the said 30 closing element is centered into the uninterrupted path of a jet from the nozzle to prematurely flare the same and to utilize its lifting force.

6. In a well pump the combination of a flow pipe, a fluid conduit terminating in an upwardly 35 directed nozzle within the said flow pipe, a partition in the flow pipe above the said nozzle provided with an opening therethrough and a hollow cylinder provided with perforations through its wall extending upwardly from the said opening. 40

JOSEPH W. MURPHEY.
